(57) **CLAIM**

The ornamental design for a bench, as shown and described.

DESCRIPTION

This application is related to commonly assigned, co-filed U.S. design patent application Ser. No. 29/728,577, filed on Mar. 19, 2020, by Chipman et al. and entitled "Bench"; U.S. design patent application Ser. No. 29/728,579, filed on Mar. 19, 2020, by Chipman et al. entitled "Bench"; U.S. design patent application Ser. No. 29/728,580, filed on Mar. 19, 2020, by Chipman et al. and entitled "Bench"; U.S. design patent application Ser. No. 29/728,581, filed on Mar. 19, 2020, by Chipman et al. and entitled "Bench"; U.S. design patent application Ser. No. 29/728,582, filed on Mar. 19, 2020, by Chipman et al. and entitled "Bench"; U.S. design patent application Ser. No. 29/728,591, filed on Mar. 19, 2020, by Chipman et al. and entitled "Bench"; U.S. design patent application Ser. No. 29/728,593, filed on Mar. 19, 2020, by Chipman et al. and entitled "Bench"; U.S. design patent application Ser. No. 29/728,594, filed on Mar. 19, 2020, by Chipman et al. and entitled "Bench"; and U.S. design patent application Ser. No. 29/728,595, filed on Mar. 19, 2020, by Chipman et al. and entitled "Bench"; which applications are hereby incorporated herein by reference in their entirety.

FIG. 1 is a perspective view of a bench in accordance with the new design;

FIG. 2 is a front elevational view thereof;

FIG. 3 is a right side elevational view thereof, a left side elevational view being a mirror image thereof;

FIG. 4 is a rear elevational view being a mirror image thereof;

FIG. 5 is a top view thereof;

FIG. 6 is a bottom view thereof; and,

FIG. 7 is a second embodiment of the bench shown with a symbolic break in length.

The broken lines shown in FIGS. 1-7 illustrate environment and form no part of the claimed design. The jagged broken lines shown in FIG. 7 represent a symbolic break in length of the article and form no part of the claimed design.

1 Claim, 7 Drawing Sheets
